[57] CLAIM

The ornamental design for a container body, substantially as shown and described.

DESCRIPTION

FIG. 1 is a front elevational view of a container body showing my new design, the rear elevational view, right side elevational view and left side elevational view being identical in appearance to the front elevational view;

FIG. 2 is a top plan view thereof; and

FIG. 3 is a view thereof in longitudinal cross section as taken in a plane including a center line.

FIG. 1

FIG. 3

FIG. 2
